UNITED STATES PATENT OFFICE.

HORACE LEONARD SHORT, ALBERT EUSTACE SHORT, AND HUGH OSWALD SHORT, OF BATTERSEA PARK, LONDON, ENGLAND.

AEROPLANE.

1,002,002.

Specification of Letters Patent. Patented Aug. 29, 1911.

Application filed June 21, 1910. Serial No. 568,163.

To all whom it may concern:

Be it known that we, HORACE LEONARD SHORT, ALBERT EUSTACE SHORT, and HUGH OSWALD SHORT, subjects of the King of Great Britain, residing at Battersea Park, in the county of London, England, have invented certain new and useful Improvements in Aeroplanes, and of which the following is a specification.

10 Various means have been proposed for preserving or governing the lateral balance of aeroplanes, a means well known being the warping of the planes or portions of them in order to vary the angle of incidence of some portion of the said planes and thereby to produce the required turning movement of the planes about the longitudinal axis of the machine or vessel by which they are carried.

20 Now the object of the present invention is to provide novel or improved devices for effecting and carrying out this balancing of the aeroplane about the longitudinal axis of the machine in a simple and effective manner, and which shall not call for the warping of the planes or for the varying of the angle of incidence of integral portions of the said planes but which devices according to the present invention shall have for their office the varying of the lifting power of the said aeroplanes upon each side of the longitudinal axis of the machine by partially cutting off or obstructing the air supply flowing to the forward part of the aeroplane surface either above or below the same, and thereby cause the shifting of the greater vertical component of the lifting force to either one side or other of the center of gravity of the said machine.

30 According to this invention, and as for example applied to that class of machine known as a bi-plane flying machine, and in which each main aeroplane is curved from its front edge to its rear edge, comparatively small air obstructing shields pivoted about the front edge of the main plane are provided. These shields are governed by suitable mechanical devices operable by the aviator, and are, when in their normal position edgewise to the direction of motion of the flying machine, so that they are or may be substantially inoperative. The shields are so located that when turned into what may be called a vertical position, one of the edges of such air shields will be near to or

in contact with the forward edge of the main aeroplane with which they co-act while the other edge will extend slightly below a horizontal plane cutting the rear edge of the said main aeroplane, and it will be observed that when so located, the lifting power of that aeroplane will be greatly decreased or comparatively nullified. With such a device, when one side of the main aeroplane descends, the shields upon the opposite side would be brought to or toward their vertical positions and thereby the lifting effect of the higher side of the main aeroplane would be reduced and the said aeroplane rocked toward a horizontal position about the longitudinal axis or line of flight, and by so operating the said air shields on one side or the other as required, the lateral balancing effect is obtained without warping, bending, or giving motion to parts of the main aeroplane.

25 The invention will be further described with reference to the accompanying drawings, whereon—

35 Figures 1 and 2 are respectively longitudinal vertical section and part front elevation showing the two main aeroplanes of a bi-plane flying machine with so much of our invention applied thereto as will be necessary for the purposes of this description. Fig. 3 is a longitudinal section of one of the aeroplanes showing an air shield according to this invention located with its pivots above the main aeroplane, and Fig. 4 is a similar view showing air shields pivoted both above and below the main aeroplane. Figs. 5 and 6 are similar views showing air shields hinged to the forward edge of the main aeroplane and illustrated in the position in which they are turned to coincide and fit against the said aeroplane, and Fig. 7 is a similar view showing the application of two of such air shields hinged to the edge of the aeroplane and arranged the one to be turned upwardly above the aeroplane and the other to be turned downwardly below it. Fig. 8 is a diagrammatic plan view indicating a flying machine in order to show the location of the air shields when applied thereto.

40 The present invention is shown as applied to that type of machine indicated in diagram for instance at Fig. 8, which has an aeroplane or aeroplanes indicated at 1, 2 extending laterally upon each side of a longi-

tudinal axis, there being a suitable vertical rudder or rudders 3 for lateral steering and a horizontal rudder or rudders 4 for steering in the vertical plane, the machine also being fitted with a suitable motor for driving a propeller or propellers 5. Such machines are further fitted with means for lateral balancing, that is for controlling the position of the laterally extending planes 10 about the longitudinal axis coincident with the direction of flight, and it is to these means which the present invention particularly relates and which will now be described.

Referring to Figs. 1 and 2 air shields are provided, which in the example shown are pivoted to the framework 7 of the main aeroplane, and the pivots 8 are so located that when the shield 6 is turned about the same 15 in the direction of the arrow, one of its edges will closely approach or contact with the forward edge of the main aeroplane 1. Means are provided for operating the air shields 6, that is for rocking the same about their pivots 8 as required, and although we do not limit ourselves to the precise construction of such means, yet in the drawings we have illustrated at Fig. 1 a spring 9 which tends to draw the shield 6 to its normal position as shown, in which position the said 20 plane abuts against a stop 10 on the framework 7. A set of air shields 6 is pivoted on each side of the longitudinal center line, and each pivot is carried in bearings in the 25 framework and provided with an arm such as 11, which by means of a cord 12 and a hand-lever 13 can be rocked by the aviator to bring the air shields 6 into more or less a vertical position.

The air shields are indicated in Fig. 8 by the numeral 14 on one side of the machine, and by the numeral 15 on the other side, and those air shields upon one side are operated by one hand-lever such as 13, and those on 40 the other side by a similar hand-lever, one of such hand-levers being located at 16 (Fig. 8) and the other hand-lever at 17, although the position of such levers may be varied to suit different circumstances as will be 45 well understood. Instead of employing two hand-levers 16 and 17 for adjusting the air shields 14 and 15 independently of each other, a single lever can be employed, the rocking of the said lever in one direction 50 moving an arm or other connection operating one set of air shields while the movement of the lever in the opposite direction moves an arm or other connection operating the other set of air shields. With this apparatus, when one side of the main aeroplane 55 descends, say the side having the air shields marked 14, Fig. 8, the air shields 15 on the other side of the main aeroplane are then brought to or toward their vertical 60 positions by means of the hand-lever lo-

cated at 17 (Fig. 8) or other suitable gear, and thereby the lifting effect of that side of the aeroplane having the air shields 15, Fig. 8, would be reduced and the machine would be rocked about its longitudinal axis or line of flight toward a horizontal position, and by so operating the air shields either on one side or the other as required, the lateral balancing effect is obtained and this without warping, bending or giving motion to parts 75 of the main aeroplane or aeroplanes.

It will be observed that when the machine is in motion with the air shields in their normal position, the air has free access to the under and upper surface of the 80 main aeroplane, and produces the usual lifting effect, but if the air shields 6 on one side of the longitudinal center of the main aeroplane are moved toward a vertical position, they obstruct the passage of the air to 85 the under surface of that portion of the main aeroplane, and if the air shields 6 are brought so that their edges contact with the forward edge of the main aeroplane, the lifting effect of that part of the aeroplane 90 will be completely nullified, and the proportions of the air shields 6 should be such that when in this vertical position, their lower edges should be somewhat lower than the rear edge of the main aeroplane. 95

Instead of arranging the air shields as at Figs. 1 and 2, they may be arranged as at Fig. 3, where they are located as indicated at 18, above the main aeroplane, and they may be operated by means similar to that 100 described with reference to Figs. 1 and 2. In this position the effect is reversed since when moved in the direction of the arrow so that the free edge approaches or contacts with the front edge of the main aeroplane, the lifting effect of the main aeroplane is increased, while when in the position shown its effect is practically neutral, although it is proposed to generally construct the air shields of a formation in 105 longitudinal section similar to the main aeroplanes, so that they may have a small lifting effect when in what we have termed the neutral position. With such a location when one side of the main aeroplane descends, the air shields 18 Fig. 3 on that side (located above the main aeroplane) would be brought to or approaching their vertical position, and thereby the force tending to 110 lift that side of the main aeroplane would 115 be increased.

The action of the air shields is not the same as an aileron but they act as valves or obstructors, their office being to obstruct the air passing to the surface of the main plane either above or below, and thus cause a diminution of pressure on such main plane surface as may be behind them. Thus by obstructing the flow of air to the lower side 125 of a portion of an aeroplane, that portion 130

receives a less lifting effect than when the air is not so obstructed, and when obstructing the flow of air to the upper side of a portion of an aeroplane the said portion is exposed to a diminution of pressure caused by the vortex action due to such obstruction.

At Fig. 4 the air shields 6 and 18 are fitted both above and below the main aeroplane, and with this arrangement when the lifting effect of one side of the aeroplane is to be decreased, the lower air shields 6 on that side alone are operated to bring them to or toward a vertical position, while to increase the lift of the main aeroplane 15 upon that side, the upper air shields 18 alone are brought to or toward a vertical position.

Instead of pivoting the air shields as indicated in the previous figures, it will be obvious that they may be hinged or pivoted adjacent to the forward edge of the main aeroplane, the lifting effect of which they are intended to control, and at Fig. 5 one 25 of the air shields 6 whose action is to be equivalent to that illustrated at Fig. 1 is so shown, while at Fig. 6 an air shield 18 equivalent to that shown at Fig. 3 is illustrated so pivoted to the forward edge of the main aeroplane, and these air shields 30 shown at Figs. 5 and 6 we form so that normally when in their inoperative positions they lie against the main aeroplane and do not have any substantial retarding effect on the flight of the machine.

At Fig. 7 the air shields 6 and 18 are shown both hinged to the forward edge of the main aeroplane and operate substantially as described and shown at Fig. 4 of the accompanying drawings.

What we claim as our invention and desire to secure by patent is:—

1. An aeroplane, comprising in combination, a main plane carrying a frame, air shields, pivots on the forward edges of said shields, means located at the forward edge of said main plane for carrying said pivots so that the latter are parallel with said forward edge of said main plane, and operating means accessible to the aviator by which each shield can be turned about said pivots into a position with relation to said front edge of said main plane to obstruct the passage of air to the forward portion of one surface thereof to alter the lifting effect of one side or the other of said main plane to obtain lateral balance of the machine.

2. An aeroplane, comprising in combination a main plane carrying a frame, air shields, pivots on the forward edges of said shields, means located at the forward edge of said main plane for carrying said pivots parallel with said forward edge and at such a distance therefrom that the free edges of said shields when turned will contact with

the front edge of said main plane, and operating means accessible to the aviator by which each shield can be turned about said pivots into a position with relation to said front edge of said main plane to obstruct 70 the passage of air to the forward portion of one surface thereof to alter the lifting effect of one side or the other of said main plane to obtain lateral balance of the machine.

3. An aeroplane, comprising in combination a main plane carrying a frame, air shields, pivots on the forward edges of said shields, means for supporting said pivots directly upon and parallel with the forward 80 edge of said main plane so that the free edges of the shields can be turned away from said main plane, and operating means accessible to the aviator by which each shield can be turned about said pivots into 85 a position with relation to said front edge of said main plane to obstruct the passage of air to the forward portion of one surface thereof to alter the lifting effect of one side or the other of said main plane to obtain 90 lateral balance of the machine.

4. An aeroplane, comprising in combination a main plane carrying a frame, air shields, pivots on the forward edges of said shields, means for supporting said pivots 95 below and parallel with the forward edge of said main plane so that the free edges of said shields can be turned to contact with the lower surface of the front edge of said main plane, and operating means 100 accessible to the aviator by which each shield can be turned about its pivots into a position with relation to said front edge of said main plane to obstruct the passage of air to the forward portion of the lower surface 105 thereof to obtain lateral balance of the machine.

5. An aeroplane, comprising in combination a main plane carrying a frame, air shields, pivots on the forward edges of 110 said shields, bearings on said frame to carry said pivots parallel with and at a distance below said forward edge of said main plane so that the free edges of said shields can be turned to contact with the lower surface of 115 the front edge of said main plane, a stop on said frame, elastic means to normally retain said shields against said stop in a position so that said shields are approximately parallel with said main plane, and 120 operating means accessible to the aviator by which each shield can be turned about its pivots into a position with relation to said front edge of said main plane to obstruct the passage of air to the forward portion 125 of the lower surface thereof to obtain lateral balance of the machine.

6. An aeroplane, comprising in combination a main plane carrying a frame, air shields, pivots on the forward edges of said 130

shields, means for supporting said pivots above and parallel with the forward edge of said main plane so that the free edges of said shields can be turned to contact with 5 the upper surface of the front edge of said main plane, and operating means accessible to the aviator by which each shield can be turned about its pivots into a position with relation to the said front edge of said main 10 plane to obstruct the passage of air to the forward portion of the upper surface thereof to obtain lateral balance of the machine.

7. An aeroplane, comprising in combination a main plane carrying a frame, air 15 shields located above and below the forward edge of said main plane, pivots on the forward edges of said shields, means for supporting the pivots of said shields which are located above the forward edge of said main 20 plane at such a distance therefrom that the free edges of said shields when turned down will contact with the upper part of the front edge of said main plane, and means for supporting said shields which are located below the front edge of said main 25 plane at such a distance therefrom that the free edges of said shields when turned up will contact with the lower part of the front edge of said main plane, and operating 30 means accessible to the aviator by which each shield can be turned about its pivots into a position with relation to the said front edge of said main plane to obstruct the passage of air to the forward portion 35 of the upper and lower surfaces thereof to obtain lateral balance of the machine.

8. An aeroplane, comprising in combination a main plane carrying a frame, air shields having their surfaces normally in 40 contact with the under-surface of the front portion of said main plane, pivots on the forward edges of said shields, means for supporting said pivots directly upon and parallel with the forward edge of said main 45 plane so that the free edges of said shields can be turned away from the under-surface of said main plane, and operating means accessible to the aviator by which each shield can be turned about its pivots into a position with relation to the said front edge of 50

said main plane to obstruct the passage of air to the forward portion of the under-surface thereof to obtain lateral balance of the machine.

9. An aeroplane, comprising in combination a main plane carrying a frame, air shields having their surfaces normally in contact with the upper surface of the front portion of said main plane, pivots on the forward edges of said shields, means for supporting said pivots directly upon and parallel with the forward edge of said main plane so that the free edges of said shields can be turned away from the upper surface of said main plane, and operating means 65 accessible to the aviator by which each shield can be turned about its pivots into a position with relation to the said front edge of said main plane to obstruct the passage of air to the forward portion of the upper 70 surface thereof to obtain lateral balance of the machine.

10. An aeroplane, comprising in combination a main plane carrying a frame, air shields having their surfaces normally in contact with the upper and lower surfaces of the front edge of said main plane, pivots on the forward edges of said shields, means for supporting said pivots directly upon and parallel with the forward edge of said 80 main plane so that the free edges of said shields can be respectively turned away from the upper and lower surfaces of said main plane, and operating means accessible to the aviator by which each shield can be 85 turned about its pivots into a position with relation to the said front edge of said main plane to obstruct the passage of air to the forward portion of both the upper and lower surfaces thereof to obtain lateral balance of the machine. 90

In witness whereof we have hereunto set our hands in the presence of two witnesses.
